FURNACE WALL

Frank Burr Bigelow, Detroit, Mich., assignor to
 Bigelow-Liptak Corporation, Detroit, Mich., a
 corporation of Michigan

Application August 21, 1939, Serial No. 291,173

5 Claims. (CL. 72—101)

The current invention relates to the upright or erect refractory or brick walls of furnaces and it pertains more particularly to novel and improved means in the wall when originally erected and for repairing such walls when their refractories or tiles become damaged or injured in service.

An aim of the invention is to provide a wall of this character which is comparatively simple and economical in structure and which may be easily repaired at relatively small cost.

In order that the invention in its generic aspects may be readily understood, both structurally and functionally, by those skilled in the art, a number of embodiments thereof have been presented in detail in the accompanying drawings forming a part of this specification and throughout the several views of which like reference numerals have been employed to designate the same parts.

In these drawings:

Figures 1 to 4 inclusive illustrate one embodiment of the invention, Figure 1 constituting a partial vertical section on the offset section-line 1—1 of Figure 4, Figure 2, a fragmentary isometric view from the outside of the wall, Figure 3, a sectional plan view on line 3—3 of Figure 1, and Figure 4, a partial elevation elevation of the wall from the outside showing a portion of its method of installation.

Figure 1A shows one of the blocks or refractories 46 in perspective, and Figure 1B presents one of the blocks or refractories 47 in similar manner.

Figures 5 to 7 inclusive portray a modified form of wall, Figure 5 being a partial vertical section similar to Figure 1, Figure 6, an isometric view from the outside of the wall, and Figure 7, a partial plan section on line 7—7 of Figure 5 on a reduced scale.

Figures 5A and 5B illustrate the blocks 46 and 47 in perspective respectively and of somewhat smaller size than those shown in Figures 1A and 1B.

Figures 8 to 10 embrace present a further modified type of wall, Figure 8 being a vertical section similar to Figure 1, Figure 9, a fragmentary isometric view, and Figure 10, a section on line 10—10 of Figure 8 on a reduced scale.

Figures 8A and 8B present the two blocks or bricks 81 and 82, respectively, in perspective.

Figure 11 is a fragmentary vertical section of another form of wall.

Referring first to the species of wall presented in Figures 1 to 4 inclusive, it will be observed that

the refractory-supporting metal-framework comprises the usual, spaced-apart, upright I-beams 21, 21 to the inner flanges of which vertically-separated, horizontal Z-bars 22, 22 are fastened by means of bolts or rivets 23, 23 extended through holes of the upstanding, outer flanges 24, 24 of such bars, which may be slotted at 25, 25, whereas the depending, inner flanges 26, 26 of the bars may be discontinuous or intermittently cut away at 27, 27, the webs 28, 28 of such horizontal bars 10 being disposed level.

Mounted on such Z-bar webs are a number of bricks or refractories 29, 29 each of which at its top has an upstanding projection 31 which is retained behind the downwardly-extended flange 15 26 on the next higher Z-bar 22, whereby such bricks overhang the webs on which their outer sections bear, the under surface of each such brick being recessed at 32 thereby providing a portion located in front of the flange 26 of the 20 bar which supports the brick.

Each brick 29 has an inwardly-extended, flat, top surface 33, a connecting vertical face 34, an inwardly, upwardly, sloping surface 35, an inner, vertical face 36, and a flat bottom surface 37.

Hung and supported on the inclined ledges 35 of such bricks is a row of inner bricks 38, 38 of the shape shown and each having an upper projection 39 with an oblique underface 41 resting on the surface 35, the top of each such brick having stepped, horizontal surfaces 42, 43, a straight, upright, inner face 44, and a plane bottom face 45 located slightly above the plane of the faces 37 of the other bricks 29.

As is fully indicated in Figure 3, some, or all of, bricks 38, 38 may be narrower than their supporting bricks 29, 29, and the joints between the former are arranged out of register with the joints between the latter.

As is indicated in Figure 4, the bricks 29, 29 are mounted on the Z-bars by temporarily tilting such bricks sidewise in the plane of the wall, and, when they are brought to erect position, they are slid along into engagement with the 45 bricks previously mounted on the framework in the manner stated.

Obviously, the final bricks to be put in place cannot be so tilted for their introduction, and, accordingly, some of these bricks are of modified construction as explained below.

The supported bricks 29 and the associated or attendant bricks 38 mounted on them and carried thereby may unitedly be considered as a row of main bricks, as distinguished from the

other bricks of the wall about to be described.

Each auxiliary or supplemental brick mentioned for the completion of the row of main bricks is composed of two parts, 46 and 47, with a horizontal joint between them, the lower brick 46 resting on the ledge 28 and the companion upper brick 47 having its top projection 48 confined behind the flange of the next higher Z-bar, the combined bricks 46 and 47 in vertical section having the same contour of periphery as the associated main bricks 29 and 38.

Each brick or tile 46 has a series of grooves or channels 49 in its top surface parallel to the wall and each tile or brick 47 in its under surface has corresponding grooves or channels 51 registering with the grooves 49.

When the cement or the like with which these companion, mating grooves are filled, when the bricks are put in place, has set or hardened, the two parts or sections 46 and 47 are locked together, whereby the upper brick 47 held in place by the Z-bar flange acts to maintain the lower brick 46 in position.

So-called "soap" bricks 52 are mounted on top of the bricks 29, 38 and 47 in front of each flange 26 and other bricks 53 with stepped top and bottom faces are positioned in front of the bricks 52 and are supported directly by bricks 38 and 47, the vertical joints between the bricks 52, 53 and those between the bricks 53, 53 being staggered as illustrated.

The main bricks, composed of the two parts 29 and 38, having been mounted in the indicated manner on the metal framework, the final space is occupied by the few bricks 46 and 47 which may be directly inserted in position from the outside of the wall without tilting them, the lower brick 46 in each instance being put in place, after which its companion brick 47 is inserted in position, the two being held firmly in place by the cement locking keys occupying the matching grooves.

In some cases, it may be possible to complete the wall using bricks 29 and 38 without any bricks 46 and 47, but, in any case, when it becomes necessary to replace any of the damaged bricks 46 and 47 or 29 and 38, then bricks 46 and 47 will be used for that purpose.

Figures 5, 6 and 7 illustrate a somewhat similar wall incorporating the following differences:

Instead of using rows of two separate bricks or tiles 52, 53, the modified construction employs a row of single bricks 61 each of which comprises a thicker inner section 62 and a thinner outer portion 63, the latter being offset longitudinally of the row with relation to the former to provide displaced joints between the ends of the bricks, these joints being staggered with relation to the joints between the bricks immediately above and below them.

The bricks of this type of wall are installed and replaced in substantially the same manner as described above in connection with the other wall.

In Figures 8, 9 and 10, a single-brick thickness wall is presented, the metal framework being the same as in the previous instances.

In this case each main brick or refractory 71 rests at its outer portion on the web of the Z-bar and its top has an upstanding projection 72 confined and retained behind the downwardly-directed flange of the next higher Z-bar, the brick in register with the flange having a groove 73 which, by its accommodation of the flange, permits the rocking of the brick in the plane of

the wall, to allow its secure mounting on the metal framework.

The part of each such brick inwardly of the furnace beyond the groove has a top flat face 74 and one upright face of each such brick has a wide rib 75 and its opposite face has a corresponding groove or channel 76, whereby the bricks, when in place, interlock with one another, in that the groove of each brick accommodates the rib of the next adjacent brick, and, in addition, the under surface of each such brick is stepped at 77.

Filler or intermediate bricks 78 having flat bottom surfaces rest on the bricks 71 and have stepped top faces 79 conforming to the under surfaces of the main bricks, all as is fully illustrated, these filler-bricks being located in front of the down-turned flanges of the Z-bars, the joints between the ends of these filler-bricks, being staggered with reference to the joints of the main bricks above and below.

The replacement bricks, in this instance, comprise two parts 81 and 82, each having on one face a groove 83 and 84, respectively, which are in register or alignment with one another and unitedly or conjointly conform to the grooves 76 of the main bricks.

As in the case of such main bricks, the bottom face of each lower brick 81 is stepped or offset at 85 to receive the adjacent filler-brick 78 and the top of each upper brick 82 has a projection 86, a groove 87 and a flat top surface 88 corresponding to the comparable parts 72, 73 and 74 of the main bricks.

As in both of the structures hereinbefore described the top surface of the lower brick 81 has a plurality of channels 89 in its top face and the bottom surface of the upper brick 82 has matching or mating channels 91 for the cement or mortar keys to lock the two bricks together, so that they may function approximately the same as a single unit brick, in that the retaining and confining property of the upper brick is transferred to the lower brick and the supporting action of the lower brick is transmitted to the upper brick, and, of course, in addition, the keys act as effective sealing means for the joint.

As will be readily understood, when the original three divided bricks, each composed of the two parts 81 and 82, are placed in the wall after the main bricks have been installed, the grooves 83 and 84 of one such divided brick receive the rib or projection 75 of the adjacent brick 71, the like grooves of the other two divided bricks being left vacant or filled with cement or mortar as may be preferred.

After the wall has been completed in the manner indicated, if any of the auxiliary bricks become damaged or require replacement, the substitution of new divided supplementary bricks for the removed injured ones may be readily accomplished from the outside of the wall, and, on the other hand, if any of the main bricks need replacement with new bricks, the described divided auxiliary bricks may be substituted therefor, but more than one main brick would require removal before such replacement could be effected due to the presence of the interlocking ribs and grooves on the main bricks.

In Figure 11, a still further modified structure is presented in which the wall is of single-brick thickness and in which the framework is like that hereinbefore set forth.

In this construction all bricks are alike with the exception that the auxiliary divided bricks

are like the main bricks except for their being in two parts to permit their insertion in place from the outside of the wall.

Each such main brick or tile 91 rests on the web of the Z-bar and has a top or upstanding extension 92 behind the holding flange of the next bar, the upper surface of such refractory in front of such projection being downwardly stepped at 93.

At its lower part, each brick 91 is in front of the inner flange of the Z-bar and extends down beyond the lower margin of the flange, its bottom surface being offset or stepped at 94 to match or mate the top surface of the next lower brick.

Each sectioned, auxiliary brick 95, 96 is of the same contour, but is divided into lower and upper parts with a horizontal joint 97 between them fitted with companion grooves or channels 98 designed to receive the sealing and locking hardened cement or mortar.

In this case, the bricks are inserted and replaced in the manner hereinbefore specified and when replacement of main bricks is required by divided auxiliary bricks, it is necessary to temporarily remove the insulation backing 99.

If desired, the main bricks may have cooperating ribs or grooves on their proximate vertical faces, and the auxiliary bricks may have comparable grooves as indicated in one of the other embodiments of the invention.

It is to be noticed that in all of the structures illustrated and described, the joint between the two parts of each auxiliary or replacement brick is horizontal to obtain a maximum binding effect between the two sections or parts of the brick, whereby to obtain as nearly as possible, the results which would accrue were the brick a unitary element, the division of the brick into sections being for the purpose of allowing the lower section to be put in place and then the companion upper section which locks the two in position, such replacement being capable of accomplishment from the outside of the wall.

Although Z-bars have been shown and described, as constituting the metal supporting means for the bricks, it will, of course, be understood that other means capable of accomplishing the same function may be used instead.

This invention, as incorporated in the specific examples presented and to which it is not limited, is set forth in the appended claims, but it will be apparent to those acquainted with this art that many major or minor mechanical changes may be resorted to without departure from the principles of the invention and without the loss of any of its substantial benefits or the sacrifice of any of its material advantages.

I claim:

1. In a furnace-wall, the combination of a metal framework including a number of horizontal vertically-spaced bars each having a brick-supporting ledge for one row of main bricks and a depending flange for retention of the next lower row of main bricks, a row of main bricks mounted on each of said ledges and overhanging said framework, each of said bricks having a top upstanding projection confined in position by the flange of the next higher bar, at least a portion of each of said main bricks being capable of being thus positioned by temporarily tilting it in the plane of the wall during its insertion in place, one or more spaces between the main bricks of each row being occupied by auxiliary bricks each of substantially the same contour as the main

brick but divided horizontally into sections to permit their introduction in position from the outside of the wall, like auxiliary bricks being adapted to be inserted in the same manner from the outside of the wall to replace any damaged main bricks.

2. In a furnace-wall, the combination of a metal framework including a number of horizontal vertically-spaced bars each having a brick-supporting ledge for one row of main bricks and a depending flange for retention of the next lower row of main bricks, a row of main bricks mounted on each of said ledges and overhanging said framework, each of said bricks having a top upstanding projection confined in position by the flange of the next higher bar, at least a portion of each of said main bricks being capable of being thus positioned by temporarily tilting it in the plane of the wall during its insertion in place, one or more spaces between the main bricks of each row being occupied by auxiliary bricks each of substantially the same contour as the main brick but divided horizontally into sections to permit their introduction in position from the outside of the wall, like auxiliary bricks being adapted to be inserted in the same manner from the outside of the wall to replace any damaged main bricks, the contiguous faces of each divided auxiliary brick having mating grooves filled with a cementitious material.

3. In a furnace-wall, the combination of a metal framework including a number of horizontal vertically-spaced bars each having a brick-supporting ledge for one row of main bricks and a depending flange for retention of the next lower row of main bricks, a row of main bricks mounted on each of said ledges and overhanging said framework, each of said bricks having a top upstanding projection confined in position by the flange of the next higher bar, at least a portion of each of said main bricks being capable of being thus positioned by temporarily tilting it in the plane of the wall during its insertion in place, one or more spaces between the main bricks of each row being occupied by auxiliary bricks each of substantially the same contour as the main brick but divided horizontally into sections to permit their introduction in position from the outside of the wall, like auxiliary bricks being adapted to be inserted in the same manner from the outside of the wall to replace any damaged main bricks, the adjacent vertical faces of said main bricks having interfitting ribs and grooves, one vertical face of said divided auxiliary bricks having a groove to receive the rib of the next adjacent main-brick.

4. In a furnace-wall, the combination of a metal framework including a number of horizontal vertically-spaced bars each having a brick-supporting ledge for one row of main bricks and a depending flange for retention of the next lower row of main bricks, a row of main bricks mounted on each of said ledges and overhanging said framework, each of said bricks having a top upstanding projection confined in position by the flange of the next higher bar, at least a portion of each of said main bricks being capable of being thus positioned by temporarily tilting it in the plane of the wall during its insertion in place, one or more spaces between the main bricks of each row being occupied by auxiliary bricks each of substantially the same contour as the main brick but divided horizontally into sections to permit their introduction in position from the outside of the wall, like auxiliary bricks being

- adapted to be inserted in the same manner from the outside of the wall to replace any damaged main bricks, the contiguous faces of each divided auxiliary brick having mating grooves filled with a cementitious material, one vertical face of said divided auxiliary bricks having a groove to receive the rib of the next adjacent main brick, the adjacent vertical faces of said main bricks having interfitting ribs and grooves.
- 10 5. In a furnace-wall, the combination of a metal framework including a number of horizontal vertically-spaced bars each having a brick-supporting ledge for one row of main bricks and a depending flange for retention of the next lower row of main bricks, a row of main bricks mounted on each of said ledges and overhanging said framework, each of said bricks having a top up-standing projection confined in position by the

flange of the next higher bar, at least a portion of each of said main bricks being capable of being thus positioned by temporarily tilting it in the plane of the wall during its insertion in place, one or more spaces between the main bricks of each row being occupied by auxiliary bricks each of substantially the same contour as the main brick but divided horizontally into sections to permit their introduction in position from the outside of the wall, like auxiliary bricks being adapted to be inserted in the same manner from the outside of the wall to replace any damaged main bricks, each said main brick being composed of two sections, one of which is an outer section supported directly on the framework and the other of which is an inner section supported on said outer section.

FRANK BURR BIGELOW.
